METHOD OF AND MACHINE FOR SEPARATING TILE FROM MULTIPLE TILE UNITS

Dana A. Cannon, Sacramento, Calif.

Application November 13, 1933, Serial No. 697,814

16 Claims.

(Cl. 25—1)

This invention relates to tile separating machines for separating the scored joints of a multiple tile unit in which a number of tile have been initially formed or molded in edge to edge relation and preferably provided with scoring along the joined edges and which tile are subsequently fired in such unitary relation. In order to separate the individual tile from this multiple tile unit for use it is necessary that the unit be disjointed along the scored edges thereof. This has ordinarily been accomplished by hand labor. Such hand labor involves a considerable amount of time and also entails a considerable amount of breakage due to the fact that a blow of a mallet by hand may be too heavy or the blow is not properly directed. With such hand labor it is also necessary to strike the multiple tile unit along each line of scoring to separate the individual tile and this involves further time loss which will be avoided by the use of my power separator.

The principal object of my invention is to provide a power separator in which the multiple tile units are progressively moved past a point. At such point is provided an impact head, powered to impart rapid blows along one scored edge of the multiple tile unit, which blows are such that the rigidity of each tile will transmit the shock of the impact blows to the other scored edges. As a result all the joints between the tiles will be evenly and quickly sheared leaving the tile ready for use. The operation can be rapidly and effectively carried out and the danger of breakage of the tile substantially avoided.

A further object of my invention is to provide a machine which is completely portable and which may be readily moved from kiln to kiln. The power tile separating machine is placed directly in the kiln and therefore obviates unnecessary handling of the tile units which are to be separated.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views.

Figure 1 is a side elevation of the power tile separator.

Figure 2 is a top plan illustrating the machine

in operating position and the position of the unseparated multiple tile units advancing to the machine and the separated tile moving away from the machine.

Figure 3 is a transverse section taken on the line 3—3 of Figure 1 illustrating an unseparated multiple tile unit in the position of contact with the impact head.

Figure 4 is an end view of a multiple tile unit comprising two tile.

Figure 5 is an end view of a multiple tile unit comprising three tile.

Referring now more particularly to the characters of reference on the drawings, the numeral 1 denotes a rectangular table frame upon which are mounted wheels 2, one pair of the wheels having the axle turnably secured to the center of the frame 1 by means of the king pin and bracket 3.

The table surface comprises an endless belt 4 driven over the belt rollers 5 whose shafts 6 are journaled in the bearing blocks 7 at the ends of the frame 1. The driven endless belt 4 is supported as the table surface by the slightly concave free rolls 8 which are journaled in the roller frame 9 held by bolts 10 to the top longitudinal frame members 11.

A motor 12 bolted to the lower frame members 13 drives a belt 14 over the pulley 15 on the outer end of a transverse shaft 16 which is journaled in the bearing 17. The shaft 6 of one of the belt rollers 5 is driven at a relatively low speed from the transverse shaft 16 by suitable chain and gear reduction mechanisms generally designated 18.

Arms 19 extend longitudinally from the ends of the frame 1 and are provided with trunnions 20 adapted to receive the semi-circular notch bearings of the arms 21 which removably support the lower end of the endless belt conveyor 22. The roller shaft 23 of the conveyor 22 is provided with a sprocket gear 24 driven by the chain 25 from the sprocket gear 26 of the shaft 6. The gravity conveyor 28 is provided with the slightly concave free rolls 29 and removably supported at the lower end by the same arm and trunnion means as the conveyor 22 hereinbefore described.

A longitudinal shaft 30 is journaled in the bearings 31 on the lower frame members 13 and is driven from the transverse shaft 16 by the beveled gears 32. Mounted on the shaft 30 between the bearings 31 is a roller cam 33. A flat spring steel arm 34 is pivoted intermediate its arms on the shaft 35 which is supported by the

bearing blocks 36. This arm 34 extends below the shaft 35 in order to contact the roller cam 33. The arm 34 also extends above the surface of the endless belt 4. An impact head 37 is secured by bolts 38 to the spring steel arm 34 in transverse relation to and above the endless belt 4 and extending thereover, as illustrated in Figure 3. This impact head comprises a wooden head member 37 encircled by an iron band 37a and faced with a leather striking plate 37b.

10 A helical spring 39 under tension is suspended by eye bolts 40 from the arm 34, at a point above the shaft 35, to one of the longitudinal frame members 11. The forward stroke of the arm 34 caused by the tension of the spring 39 is limited by the rubber bumper 41 suitably held in place by a yoke 41a mounted on the other frame member 11. The motion of the arm 34 imparted by the cam 33 against the tension of the spring 39 is restricted by the bumper 42 also mounted on the frame member 11 between the ends of the arms of the yoke 41a.

15 Longitudinal guide plates 43 are adjustably mounted on the frame 11 by use of the coordinating adjustable bracket arms 44. These guide plates 43 are longitudinally positioned in a vertical plane over and above the edge of the endless belt 4 as desired and are spaced apart on the opposite sides of the impact head 37. The guide plate 43 on the side of the table where the multiple tile units advance to the endless belt 4 is curved as at 43a. The guide plate 43 in the side of the table where the tile moves away from the endless belt 4 is cut at an angle at its bottom edge where it extends over the endless belt conveyor 22 in order to avoid contact with said endless belt.

20 In operation of this power tile separator since the machine is readily portable, it is moved into the kiln where the multiple tile units have been fired. The gravity conveyor 28 is then adjusted by suitable supporting means (not shown) so as to be at an incline down to the endless belt 4.

25 The driven endless belt conveyor 22 is also adjusted by suitable support means (not shown) so that its discharge end extends out of the door of the kiln and is at any desired height from the ground in order to load the separated tile onto trucks or the like.

30 The type of kiln in which my tile separating machine is adapted to be used is that character of kiln generally known as the periodic type. The kiln with the multiple tile stacked therein is first fired and then allowed to cool before it is opened and before the workmen enter with the machine to separate the tile as hereinafter described.

35 With the tile separator thus positioned the operator switches on the electric motor 12 and this causes the endless belt 4 as well as the endless belt conveyor 22 to be put in motion at approximately the same speed by reason of the drive mechanism hereinbefore referred to. With the motor operating, the transverse shaft 16 is rapidly revolved which in turn rapidly revolves the longitudinal shaft 30 by means of the bevel gears 32. The roller cam 33 mounted on the longitudinal shaft 30 revolves with the shaft and with each revolution the roller of the cam strikes the face of the lower end of the flat spring steel arm 34 and pushes it into a position against the tension of the helical spring 39, as illustrated in outline in Figure 3. In this position the upper end of the arm 34 has come into facing contact with the bumper 42 and the spring steel arm has been given a spring effect by the cam 33 further

forcing against the lower end of the arm 34 after the upper end of the arm 34 has come to rest against the bumper 42. As the cam 33 moves still further in its circular arc the spring steel arm 34 snaps away from contact with the roller cam 33 and the combined force of the spring effect imparted to the arm 34 and the tension of the helical spring 39 gives the impact spring 37 a very high initial speed as well as an exceedingly sharp impact force. This blow is of course 10 brought to a stop by the rubber bumper 41.

15 The multiple tile units are scored inside and out along the edge of each tile as at S and may be made to comprise two tile, as at 45 in Figure 4; three tile, as at 45a in Figure 5; or otherwise as 15 manufacturing practice may require.

20 In order to separate the multiple tile unit designated generally as 45, said unit in its unseparated form is taken from the stack in the kiln and placed by hand on the upper end of the 20 gravity conveyor 28, which carries it by gravity down to the endless belt 4 where a workman standing on one side of the table facing the impact head and guide plate 43 takes a hold on each end of the tile and holds it against the guides 25 43 as it is conveyed past the impact head 37 with one scored edge of the tile held at right angles to the rapidly reciprocating impact head 37. As the impact head strikes the multiple tile unit along one such scored edge the impact separates that edge and the rigidity of each tile in the unit is sufficient to withstand the shock of such impact, which shock is then in turn transmitted to the other scored edges of the tile in the unit which immediately shear apart. The position of the tile moving on the endless belt 4 before and after breaking apart is clearly shown in Figure 2, the separated tile being designated 46. The face 37b of the impact head 37 is made of leather in order that the contact with one edge 40 of a multiple tile unit may be cushioned enough to prevent breakage even though the impact is rapid and sharp.

25 If it is desired to adjust the effective length of the stroke of the impact head 37 the longitudinal 45 vertical guide plates 43 on each side of the impact head 37 may be moved laterally forward or backward depending on the adjustment desired. In practice a stroke of one-fourth inch effective length is usually sufficient to cause all the segments to shear apart at their scored edges without injury to the segments proper.

30 As the tile of the multiple tile units are separated they are at once carried away by the endless belt 4 and the belt conveyor 22 to the truck being 55 loaded, or the like.

35 From the foregoing description it will be readily seen that I have produced such a device as substantially fulfills the objects of the invention as set forth herein.

40 While this specification sets forth in detail the present and preferred construction of the device, still in practice such deviations from such detail may be resorted to as do not form a departure from the spirit of the invention, as defined by the 65 appended claims.

45 Having thus described my invention what I claim as new and useful and desire to secure by Letters Patent is:

50 1. That method of separating the individual tile of a multiple tile unit in which the tile have been initially fired together in jointed edge to edge relation, comprising the steps of first advancing a multiple tile unit past a point, and applying rapid impact strokes to one of the joints 75

of the unit as it advances and passes said point until all the tile of the unit have been separated.

2. That method of separating the individual tile of a multiple tile unit in which the tile have been initially fired together in jointed edge to edge relation while in the kiln, comprising the steps of advancing a stream of units past a point in the kiln, applying rapid impact strokes to one of the joints of each unit as it passes such point until all the tile of the multiple tile unit have been separated, and then moving the separated tile away from such point and out of the kiln.

3. That method of separating the individual tile of a multiple tile unit in which the tile have been initially fired together in jointed edge to edge relation, comprising the step of applying to one joint thereof rapid vibratory impact strokes until all the joints have been broken.

4. A mechanism for separating the individual tile of a multiple tile unit in which the tile have been initially fired together in jointed edge to edge relation, comprising means to advance the unit, an impact head, means to impart a rapid reciprocating motion to the head, and means mounting the head in position to strike one joint of the tile unit as it advances to a degree sufficient to cause separation of all the joints thereof.

5. A mechanism for separating the individual tile of a multiple tile unit in which the tile have been initially fired together in jointed edge to edge relation, comprising a support for the multiple tile unit, an impact head adjacent the support, yieldable means normally holding the impact head in one position, and means to actuate the impact head against the tension of said yieldable means in order to impart rapid impact strokes to the head.

6. A mechanism for separating the individual tile of a multiple tile unit in which the tile have been initially fired together in jointed edge to edge relation, such mechanism including a support for the tile, an arm pivoted to one side of said support, an impact head on said arm above the support, a cam operable against the arm to impart movement thereto in one direction only and yieldable means opposing the cam action whereby with the rotation of the cam the impact head will have imparted thereto rapid impact strokes.

7. A mechanism for separating the individual tile of a multiple tile unit in which the tile have been initially fired together in jointed edge to edge relation, such mechanism including a support for the multiple tile unit, an arm pivoted to one side of said support, an impact head on said arm above the support, means to impart to the arm a rapid back and forth motion comprising a cam to move the arm in one direction, a spring acting in the opposite direction, and a stop to limit the stroke of the arm against the spring tension; the cam being arranged to spring the arm after said arm has come to rest against said stop.

8. A mechanism for separating the individual tile of a multiple tile unit in which the tile have been initially fired together in jointed edge to edge relation, comprising a support for the multiple tile unit, an impact head adjacent the support, means to impart strokes to the head, and means to position one edge of the multiple tile unit in the path of the stroke of the impact head.

9. A mechanism for separating the individual tile of a multiple tile unit in which the tile have

been initially fired together in jointed edge to edge relation, comprising a support for the multiple tile unit, an impact head adjacent the support, means to impart strokes to the head, and a guide to position one edge of the multiple tile unit in the path of the impact head stroke. 5

10. A mechanism for separating the individual tile of a multiple tile unit in which the tile have been initially fired together in jointed edge to edge relation, comprising a support for the multiple tile unit, an impact head adjacent the support, means to impart strokes to the head, and longitudinal guides adjacent the impact head and suspended over the support to position one edge of the multiple tile unit in the path of the impact head stroke. 10

11. A mechanism for separating the individual tile of a multiple tile unit in which the tile have been initially fired together in jointed edge to edge relation, comprising a support for the multiple tile unit, an impact head adjacent the support, means to impart strokes to the head, longitudinal guides adjacent the impact head and suspended over the support to position one edge of the multiple tile unit in the path of the impact head stroke, and means to adjust such guides in relation to the length of the stroke of the impact head. 15

12. A portable device for separating multiple tile units adapted to be removably positioned in a kiln, comprising a support for the multiple tile units, means mounted in connection with the support to separate the individual tile from each multiple tile unit, a conveyor leading to one end of the support to deliver the multiple tile units 35 thereto, and a conveyor leading from the opposite end of the support to carry away the separated tile.

13. A structure as in claim 12 with means removably mounting said conveyors in connection with the support. 40

14. A portable device for separating multiple tile units adapted to be removably positioned in a kiln, comprising a support for the multiple tile units, means mounted in connection with 45 the support to separate the individual tile from each multiple tile unit, said support including an endless driven conveyor; a movable ground engaging frame on which the conveyor is mounted, a second conveyor mounted on the frame and leading to one end of the first conveyor to deliver the multiple tile units thereto, another endless driven conveyor mounted on the opposite end of the frame and leading away from the first named conveyor, and power means mounted on the frame to actuate the tile separating means and to drive the endless driven conveyors. 50

15. The method of separating the individual tile of a multiple tile unit in which the tile have been initially fired together in jointed edge to edge relation, comprising the step of applying rapid vibratory impact strokes to said multiple tile unit along one joint-edge thereof. 60

16. A mechanism for separating the individual tile of a multiple tile unit in which the tile have been initially fired together in jointed edge to edge relation, comprising means to support and advance the unit, and means mounted adjacent the support to impart impact strokes to the unit along one joint-edge thereof as the unit advances. 65
